ATTORNEY'S

UNITED STATES PATENT OFFICE.

BENJAMIN F. CARGILL, OF CARNEGIE, PENNSYLVANIA.

INVALID-COT.

SPECIFICATION forming part of Letters Patent No. 629,658, dated July 25, 1899.

Application filed March 16, 1899. Serial No. 709,276. (No model.)

To all whom it may concern:

Be it known that I, BENJAMIN F. CARGILL, a citizen of the United States of America, residing at Carnegie, in the county of Allegheny 5 and State of Pennsylvania, have invented certain new and useful Improvements in Invalid-Cots, of which the following is a specification, reference being had therein to the accompanying drawings.

10 My invention relates to certain new and useful improvements in operating cots for invalids.

15 The object of my invention is to construct a cot of this character with means for turning an invalid upon his back without causing any inconvenience.

20 A further object of my invention is to construct a cot which after the invalid has been turned upon his back can be lowered to the position desired.

25 A further object of my invention is to construct a cot for turning an invalid upon his back and for securely locking the cot in the desired position.

30 My invention finally consists in the novel combination and arrangement of parts hereinafter more fully described, and particularly pointed out in the claims.

35 In describing the invention in detail reference is had to the accompanying drawings, forming a part of this specification, wherein like numerals of reference indicate corresponding parts throughout the several views thereof, and in which—

40 Figure 1 is a perspective view of my improved invalid-cot, showing the operating parts therefor, the lower cot being removed. Fig. 2 is a side view thereof, showing the operating-belt in dotted lines. Fig. 3 is a longitudinal sectional view thereof.

45 Referring to the drawings by reference-numerals, 1 indicates a series of standards which are connected by the cross-bars 2 3, forming a frame or support for the various operating parts.

45 4 indicates the supports for the lower cot 5. Mounted in the cross-bars 2 are the shafts 6 7, having the sprocket-wheels 8 mounted thereon, over which the belt or chain 9 operates.

50 The shaft 6 is provided at each end with gear-wheels 10, which mesh with the gear-wheels 11, connected to the auxiliary shaft 12, this

auxiliary shaft 12 being suitably mounted in the cross-bars 2. The shaft 6 extends through one of the cross-bars 2, as shown, and on this extending end is mounted a sprocket-wheel 13, which is engaged by the dog 14, pivotally secured to the outer face of one of the bars 2, as at 15, and spring-actuated by means of the coil-spring 16, suitably connected thereto and to the outer face of one of the bars 2. The shaft 7 is also provided with gear-wheels 17, and this shaft 7 extends outwardly through one of the cross-bars or rods 2 and is adapted to be engaged on its extending end 18 by a 65 suitable crank-handle 19 for operating the same.

20 indicates the supporting-standards for the platform 21, upon which is mounted the upper cot 22. The cot 22, as well as the cot 70 5, are connected to their platforms by means of the securing-flaps 23 operating on the fastening-pins 24. The platform 21 has formed integral with each end the shafts 25 25', which operate through the dovetailed bearing-blocks 75 26. These dovetailed bearing-blocks are adapted to be secured between the standards 20 at the upper end thereof. The shaft 25 is adapted to receive a suitable crank-handle 80 for revolving the same. The outer end of the shaft 25 has secured thereto the sprocket-wheel 27, which is adapted to be engaged by the bar 28, having a tapering lug 29 formed integral with one side thereof. This bar 28 holds the upper cot 22 in the desired position. 85

20 The standards 20 have the elongated slots 30 arranged therein to allow of the operation of an upward-and-downward movement through the cross-bar 3, which where they are engaged by the standards 20 is cut away 90 95 to allow of this operation, as at 31. The inner face of each of the standards is formed with a series of teeth 32, forming a rack-bar, which are engaged by the gear-wheels 11 and 17.

33 indicates a series of suitable straps secured at one end to the sides of the lower cot 5 for securing the upper cot thereto.

100 The operation of my improved invalid-cot is as follows: Assuming that the lower cot is in the position as shown in Fig. 2, the upper cot 22 is turned and lowered against the invalid, who is lying upon his back on the lower cot. The two cots are strapped together and ele-

vated by means of the handle 19 revolving the shaft 7, upon which the gear-wheels 17 are mounted. This causes the operation of the belt 9, operating the gear-wheels 11, and it will be readily observed that the gear-wheels 5 engage the rack 32, and the two cots will be elevated to the desired position, when they are turned by means of the handle engaging the shaft 25. The cots are then lowered to the 10 desired position and the cot 5 removed, the invalid then lying upon his face.

It is thought that the many advantages of my improved cot can be readily understood from the foregoing description, taken in connection with the accompanying drawings.

It will be noted that various changes may be made in the details of construction without departing from the general spirit of my invention.

Having thus fully described my invention, what I claim as new, and desire to secure by Letters Patent, is—

1. In a device of the character described a support or frame, a series of standards suitably connected thereto having their inner face formed with a rack, bearing-blocks mounted in the upper end of said standards, an upper platform having a cot pivotally mounted in the said blocks, shafts formed

integral with the said platform operating 30 through the said bearing-blocks, and means adapted to engage the said rack for elevating and lowering the said platform, substantially as set forth.

2. In a device of the character described a support or frame, a series of standards suitably connected thereto, having their inner face formed with a rack, bearing-blocks mounted in the upper end of said standards, an upper platform having a cot suitably connected thereto, shafts formed integral with said platform pivotally mounted in the said bearing-blocks, a lower platform adapted to be mounted upon said frame having a cot suitably connected thereto, means adapted 40 to engage the said rack for elevating and lowering the said upper platform to bring the cot carried thereby into engagement with the said lower cot, and means for locking the said upper cot in the desired position, substantially 45 as set forth.

In testimony whereof I affix my signature in the presence of two witnesses.

BENJAMIN F. CARGILL.
